UNITED STATES PATENT OFFICE.

VALERIUS D. ANDERSON, OF CLEVELAND, OHIO.

PRESS.

SPECIFICATION forming part of Letters Patent No. 602,928, dated April 26, 1898.

Application filed July 17, 1896. Serial No. 599,538. (No model.)

To all whom it may concern:

Be it known that I, VALERIUS D. ANDERSON, a citizen of the United States, residing at Cleveland, in the county of Cuyahoga and 5 State of Ohio, have invented certain new and useful Improvements in Presses, of which the following is a specification.

My invention relates to presses for extracting moisture, grease, &c., from garbage and 10 for like work requiring very heavy or powerful pressure, and is in the nature of an improvement upon that set forth in Letters Patent of the United States granted to me May 17, 1892, No. 474,802.

15 Among other novel features of construction may be mentioned an arrangement of the chain belt within instead of outside the main drum, the division of said belt into a plurality of parallel chains, the positive driving of said 20 chain or of one of its sections, the introduction of a crushing gage-roller, and the combination therewith of a throw-out device to stop the press in the event of a solid substance of 25 undue size passing the gage-roller. These and other features of invention will be duly pointed out and claimed.

Figure 1 is a side elevation of a press constructed in accordance with the present invention; Fig. 2, a vertical sectional view of 30 the same in a plane parallel with its side faces; Fig. 3, a vertical section in a plane at right angles to the side faces of the press; Fig. 4, a section on the line $x-x$ of Fig. 1; Fig. 5, a view illustrating the automatic belt-shifter, and Fig. 6 a detail view.

35 It has long been desired to produce a press or apparatus whereby a very large percentage of moisture, oil, grease, &c., should be quickly removed or separated from solid matters with 40 which they might be associated; but it is well known to builders of this general class of machinery that under the best conditions obtainable the percentage remaining after pressure has been quite large. As a result of very 45 large experience in the manufacture of machinery for handling garbage, offal from slaughter-houses, brewers' and distillers' grains, and the like I have learned that the pressure must be concentrated upon a small 50 surface at a time, that this must be repeated

a reasonable number of times, that the pressure should increase with each repetition, and that the pressing devices should be set progressively closer to compensate for reduction in bulk of the matter treated. In my patent 55 above mentioned these features were present in part; but the press was unduly large in proportion to its capacity, and it was incapable of giving the high efficiency which I am enabled to attain by the improved construction about to be explained.

50 A indicates a main frame which is preferably cast in one piece and of circular form, though it may be built up of separate parts, if desired. This frame supports a series of roller-housings and pressure devices, and to the end that these and other parts may be readily applied to and adjusted about the frame it is cast with two circumferential grooves *a a* 55 of T-form in cross-section, the narrower portion of the groove outward. At suitable intervals these grooves are made of full width to their outer edges, as shown in Fig. 6, in order that bolts *b* may have their heads inserted through such widened portions and 60 then moved around to any desired point in the grooves, while their stems or shanks project through the narrower portion of the 65 grooves and beyond the frame.

60 B B indicate feet or standards upon which 80 the frame A is supported and the upper flanged ends of which are made fast to the frame by a number of the bolts *b*, passing through said flanges and provided with nuts, as seen in Fig. 1.

85 C indicates a drum, ring, or circular hoop, against the inner face of which the pressing is done. This ring is made concentric with and is mounted within the frame A, sufficient clearance being left to preclude binding under any conditions that may obtain in working.

90 To support the ring, maintain it in position, and reduce to a minimum the friction to be overcome in rotating it, I provide a series of 95 rollers D, which are carried in boxes or bearings *c*, movable radially in seats formed in frame A and pressed and held inward by adjusting-screws *d*, provided with clamping or lock nuts *e*, as seen in Figs. 1, 3, and 4.

To prevent lateral displacement of the ring, hoop, or drum C, it is formed with circumferential flanges f, which extend past the ends of the rollers D, as seen in Figs. 3 and 4.

5 The rollers D are of the form shown in said Figs. 3 and 4—that is to say, they are of plain cylindrical form at their ends—to bear against a like portion of the drum or ring C and are provided with gear-teeth g at an intermediate point to mesh with teeth h, formed in the circumferential face of the ring or drum. The teeth will be sufficiently short to preclude any pressure or bearing upon their ends, the pressure in this direction being taken entirely 10 upon the plain cylindrical end portions of the rolls. By this arrangement I am enabled to give motion from one of the rolls to the ring and from the ring to all the other rolls, thus precluding any slip or sliding of the ring upon 15 the rolls, which would be apt to result in cutting or undue wear.

E indicates a driving-shaft provided with a band-wheel F and with a pinion G, which meshes with a gear-wheel H, carried by a shaft 25 I, and this shaft in turn carries a pinion J, which meshes with a gear-wheel K on the shaft of one of the rollers D, thus rotating said roll and giving motion to the ring or drum C. Obviously other suitable gearing may be employed, but that shown is what I have thus far used in practice.

Within the ring or drum C, I arrange a series of rollers L, designed to support and carry a chain belt M, between which and the inner 35 surface of the ring or drum the pressing is effected. Each roller L is carried in half boxes or blocks i, held in the open yokes of threaded draw-rods N, Figs. 1 and 3, the rods passing radially outward through tubular bosses or 40 ears j, formed at the ends of heavy castings or cross-plates O, secured to the annular frame A by bolts b in the same manner as the legs B. The rods N are screw-threaded, and at some distance beyond or outside of the 45 cross-plates O they pass through ears of similar cross-plates P, and are provided with nuts k, as shown. Between the cross-plates O and P of each pair are interposed heavy spiral springs Q, Fig. 1, which, pressing outward 50 upon the plates P, tend to carry outward the rods N and to cause the rolls L to press against chain belt M. The compression and consequent force or pressure of the springs Q is determined by adjustment of the nuts k, and 55 the outward movement of the rods and the consequent adjustment of the rolls L is determined by stop-nuts l, screwed upon the rods before they are passed through the cross-plates O P, and adjusted from time to time, 60 as required.

The boxes or blocks i move between suitable guides, as shown in Figs. 1, 2, and 3, and are thus kept in proper position.

R indicates a feed-hopper carried by the 65 frame A and containing a worm or screw S. (Shown by dotted lines in Fig. 4.) The body

of the hopper stands outside of frame A, but its delivery end is arranged within the frame and just above a gage-roller T. This roller is preferably made somewhat concave and is designed to crush such solid matters as may be introduced into the machine in pieces too large to be safely introduced between the belt and the drum. In order that it may perform this work and yet not break or strain the machine in the event of substances entering which are too hard to be crushed, its boxes i are each provided with two rods N to withstand heavy strains, and its springs Q are made heavier or more numerous than those of the initial pressing-rolls L. In other respects the manner of mounting and adjusting the roll T is the same as above explained in connection with rolls L, and the last of these are preferably provided with the double rods and heavy springs, since they are required to give heavier pressure than the first rolls of the series.

The roller T may be outside the belt M, as shown, or within the belt, though it is deemed better to place it outside.

Motion is imparted to the roller T by a gear-wheel m, keyed to its shaft and meshing with a pinion n, keyed to the shaft of one of the outside ring-supporting rolls D. The teeth 95 of these wheels are sufficiently deep to permit all necessary play of the roller T without unmeshing.

Motion is imparted to the feed-screw or worm S by a belt passing about a pulley on its shaft or in any other convenient way.

The rollers L may be arranged in any desired relation to the ring or drum C, so as to cause the pressing to be done on the upper, lower, ascending, or descending side of the 105 ring, as preferred. In the drawings the rolls are shown arranged in a semicircular series, beginning at the lower and extending to the upper side of the ring, the belt returning from one end of the series to the other in a nearly diametric line. This arrangement is deemed advantageous generally, but is not essential.

Under the arrangement thus set forth the material to be treated is delivered into hopper R and thence by screw S to the roller T and ring C, between which it is carried by their rotation. Coarse solid matters are crushed by the roller, and the mass, thus prepared, passes on to the meeting-point of belt 115 M and ring C, passing between them and being there subjected to repeated and increasing pressure as the chain passes the rolls L in succession. By this mode of alternate pressing and relieving from pressure I am 120 enabled to remove a far greater percentage of the moisture, grease, and like matters than I have been able to do under any other plan, the temporary relief from pressure permitting the particles composing the mass to rearrange 125 themselves in a measure and also to open sufficiently to release or afford an escape for 130

the fluid particles mechanically bound in the interior of the mass.

The ring C may be perforated or its flanges o, which extend inward past the ends of the rolls, may be formed with outlets for escape of the released fluids, grease, &c.; but the bulk of such matters will escape through the openings in and between the members of belt M.

10 Heretofore it has been customary to make the belt M with links or lags as wide as the entire belt; or, in other words, it has been a single-chain belt with wide links or lags. Such construction is objectionable in that it 15 does not afford free or adequate escape for the fluids or matters expressed. I obviate this difficulty by constructing the belt of a series of parallel but independent chains with relatively narrow links. In the drawings I 20 have represented four such chains constituting the belt M, and this number has been found quite satisfactory in presses thus far constructed. I do not, however, restrict myself to any specific number, but propose to 25 use any number from two upward, or a single-chain belt may be used with other features here set forth. The compound belt is deemed best, however, not only for this, but for all 30 presses of this general character using belts. Owing to the greasy character of the 35 matters handled or extracted it has been found that the belt is liable to slip or slide upon the rollers L without turning them. When this happens, the rolls are apt to be cut or to grind flat in spots, and it is impracticable thereafter to cause them to rotate, at least with certainty or regularity. To meet this difficulty, the rolls L are provided with seats or cavities p to receive teeth or projections q, formed 40 upon the links of chain or belt M, so that if the chain or belt moves at all the several rollers must turn forward at a like surface speed.

When the belt is composed of a plurality of chains, it will be sufficient to provide one of 45 them with teeth or projections. Obviously the teeth may be formed upon the rollers and the seats or cavities in the links, though I prefer the construction shown.

After the material has traversed the full 50 length of the series of rolls L it is left adhering mainly to the inner surface of ring C; though a small portion will adhere also to the belt M. To remove the material from the ring, I provide a scraper U, which is carried 55 by a rock-shaft r, mounted in suitable hangers or supports and furnished with a slotted sector-plate s, through which passes a clamping-bolt t. The shaft is so set as to bring the edge of the scraper close to the inner face of 60 the ring and is there clamped and retained until by reason of wear or from other cause it becomes necessary to reset it.

V indicates a brush, the shaft u of which passes through sleeves or boxes v, movable 65 in slots in a hanger or support W, secured to

the frame, the boxes being in the form of large tubular bolts, which can be clamped at any point in the length of the slots. The brush V is arranged to sweep the outer face of the chain belt M as the belt passes from 70 the upper roll to the lower roll L, and in order that it may do this effectively and that the belt may not fall away from it a sustaining-roller X is mounted in adjustable bearings like those of brush V and is arranged on 75 the opposite side of the belt, as seen in Figs. 1 and 2.

Y indicates a trough or hopper having its supporting-arms extended through slots in the hanger or support W, which carries the brush 80 and roll X. It is adjusted to proper position to receive the material detached by scraper U and by brush V and is furnished with a worm or screw w, by which the material is carried from the hopper or trough into any 85 convenient receptacle or delivered upon the ground or floor.

The hanger or support W is made vertically adjustable in any convenient way, a threaded stem with nuts being shown at one 90 end and a slotted arm and clamping-bolt at the other end in Fig. 1.

Motion is given to the brush V and to the worm or screw w by crossed and open belts from band-wheels on the driving-shaft E or 95 in any equivalent way.

As a means of avoiding breakage of the machinery, I may in some cases provide automatic mechanism for throwing off the driving-belt in the event of substances entering 100 the machine too large to pass beneath and too hard to be crushed by the roller T. Such a mechanism is illustrated in Fig. 5, where the roller T is represented as carried by the short arms of elbow-levers Z, the long arms 105 of which are acted upon by the springs Q through the medium of threaded rods x, provided with hand-wheels y. Rising from one of the levers Z is an arm z, provided with a stud or pin, which as the lever rises acts 110 upon a belt-shifting lever or device of any convenient sort and through it shifts the belt from a fast to a loose pulley, as will be readily understood upon reference to Fig. 5. This arrangement leaves the shipping-lever 115 free to be manually operated whenever desired.

No claim is made to the belt-shifter proper, but only to a combination of parts whereby the belt is shifted when the roller T is moved 120 beyond a given or predetermined limit.

The finishing-rollers of the series of rollers L are advisedly made of larger diameter than the initial rollers of the series in order that they may be freely turned by and with the 125 belt M, notwithstanding the greater pressure upon them.

In the practical use of presses of this class it is sometimes desirable to embody a belt of fibrous or woven material between the chain 130

and the drum, and this is contemplated in the present instance. Such a belt is indicated in Fig. 2 by dotted line.

I am well aware that it has been proposed to employ a single roller or a series of rollers within a drum for the purpose of crushing, grinding, or pressing materials contained within the drum, and I make no claim broadly thereto. Where such rollers are used within a hollow drum or cylinder, a wedge-shaped space is formed at the receiving side of the roll, between its circumference and the inner surface of the drum, and experience has demonstrated that owing to this formation and to the accumulation of material within this wedge-shaped space one of two results is inevitably produced—either the roll slips upon and fails to draw in the material or the material wedges so firmly into the space as to preclude the rotation of the roll. This fact has been demonstrated in many instances after the expenditure of large sums of money.

By the employment of the endless chain belt a pressing-space of practically uniform width or depth may be formed, the belt constituting one wall of the said space and serving to confine and keep in shape the material under treatment and preventing its escape or disarrangement in passing from one roll to another. Where the links of the belt or chain are made appreciably shorter than the space from roll to roll and the chain is placed within the drum instead of on the outside thereof, the chain or belt is enabled to yield slightly and to relieve the pressure upon the material at points between successive rolls, but without permitting the escape or disarrangement of the material held between the belt and the drum. So far as I am aware this peculiar action has never been attained by any one prior to my own invention.

Having thus described my invention, what I claim is—

1. In a press, the combination of an annular frame; a ring or drum rotatable within said frame; a series of pressure-rolls arranged within the drum; and an endless flexible belt or chain, passing between the rollers and the ring or drum, substantially as described and shown.

2. In combination with a ring or drum, an endless flexible belt or chain within the drum; and pressure devices within the belt or chain, serving to press the same toward the inner surface of the ring or drum.

3. In combination with a rotatable ring or drum, a series of pressure-rollers within the drum; and a flexible belt or chain arranged to travel between the drum and the rollers, substantially as described and shown.

4. A press, consisting of an external frame; a ring or drum within said frame; supporting rollers for said ring; an endless flexible belt or chain within the ring; a series of pressure-rollers within said belt or chain; pressure devices adapted to hold the rollers against the

belt with a yielding pressure; and means for imparting motion to the ring, the belt, and the rollers.

5. In a press, an annular frame A provided with undercut circumferential grooves *a* to receive and permit adjustment of bolts; and bolts *b* having their heads seated in said grooves, substantially as set forth.

6. In a press, a chain belt composed of a plurality of independent chains arranged side by side and in close proximity to one another, substantially as set forth.

7. In combination with an outer ring or drum, and with inner supporting or pressing rollers; an intermediate chain belt, the belt and rollers being adapted to mesh or interlock substantially as and for the purpose explained.

8. In combination with ring or drum C, internal rollers L and interposed belt M, a crushing-roll arranged to act upon the material fed to the press, before it passes between the belt and ring, to prepare it for their action.

9. In combination with a press comprising a rotatable ring, a series of rollers within the ring, and an endless flexible belt between the ring and rollers; a preliminary crushing or gage roller; yielding supports for said roller; and a belt-shifting lever or device arranged in proximity to the yielding roll-supports and serving to shift the belt whenever the gage-roller is moved a predetermined distance by the passage beneath it of unyielding substances.

10. In a press, the combination of a frame, a ring rotatable therein; an endless flexible belt within the ring; pressure-rollers within the belt; a feed trough or hopper; and a worm or screw serving to deliver material from the trough or hopper to the pressing mechanism.

11. In combination with ring C, rolls L located within said ring; intermediate belt M; a rotary brush V bearing against one face of said belt; and a supporting-roll X bearing against the opposite face of said belt.

12. In combination with ring C; rolls L within said ring; belt M between the ring and rolls; scraper U bearing against the interior of the ring; brush V in contact with belt M; and hopper Y, provided with a worm or screw, and located within the ring, substantially as described and shown.

13. In combination with ring C; belt M within said ring; rollers L within the belt; hanger W; and scraper U, brush V, and roll X all adjustably mounted in said hanger and located within the ring.

14. In combination with a press substantially such as described and shown; hangers or supports W provided with slots; boxes movable in said slots and provided with clamping-nuts; and cleaning devices carried in said boxes; all substantially as described and shown.

15. In a press, the combination of an outer

rim or drum; a series of pressure-rolls; and an endless belt, said belt passing between the rollers and the drum and being contained wholly within the latter.

5 16. In combination with a hollow or annular drum, a chain belt arranged within the same; rolls for sustaining said belt and maintaining its outer face in proximity to the inner face of the drum; and a belt of fibrous or

woven material interposed between the drum 10 and belt, substantially as set forth.

In witness whereof I hereunto set my hand in the presence of two witnesses.

VALERIUS D. ANDERSON.
